Isiah Williams, INVENTOR
BY Victor J. Evans

ATTORNEY

UNITED STATES PATENT OFFICE.

ISIAH WILLIAMS, OF GARY, INDIANA.

ELECTRIC HEATER.

Application filed July 29, 1927. Serial No. 209,324.

This invention relates to heaters for use in warming parts of the human body, an object of the invention being to provide means for keeping the feet warm, and thereby not only warming these members of the body, but by doing so, add to the warmth of the entire body.

Another object of the invention is the provision of means of the above character which may be readily secured in position for use and may be worn without discomfort.

Another object of the invention is the provision of a heater of the character stated which is simple in construction, and in which the heating element may be readily replaced.

With the above and other objects in view, the invention further includes the following novel features and details of construction, to be hereinafter more fully described, illustrated in the accompanying drawings and pointed out in the appended claim.

In the drawings:—

Figure 1 is a plan view of one of the feet warming devices.

Figure 2 is a sectional view illustrating by dotted lines the position of a shoe within the foot warmer.

Figure 3 is a section taken substantially on the line 4—4 of Figure 1.

Figure 4 is a fragmentary section showing the manner of latching the front and rear sections.

Referring to the drawings in detail wherein like characters of reference denote corresponding parts, the reference character 15 indicates generally a foot warmer or heater. This heater comprises a shell which includes a front section 16 and a back section 17, the sections being hingedly connected at adjacent edges as shown at 18. The other adjacent edges of the sections are connected by a latch 19 which is secured to one of the sections and which engages a tooth 20 carried by the other section.

The front section 16 is shaped substantially in conformity with the shape of a shoe, and is adapted to fit over the top of a shoe, while the back section 17 is shaped so as to conform substantially to the shape of the

back of a shoe. The back section extends upward above the upper edge of the front section and a strap 21 is adapted to extend

around the shoe and have its opposite ends connected to the edges of the back section. One edge of the back section carries a buckle 55 22 to provide connecting means for the free end of the strap.

Located within the front section and adapted to extend upward along the front of the shoe from the toe of the latter is a heating element. This heating element may be of a suitable type, the element shown comprising an isinglass core 23 around which is coiled a resistance wire 24. An asbestos or other insulating member 25 is positioned between 60 the resistance element and shell and the structure is removably held in place by means of attaching elements 26 located at each end of the heating element.

The back section 17 carries a holder or 70 pocket 27 within which is positioned an electric cell 28 which provides a source of current for the heating element, connection being effected by means of a conductor cord 29. The holder or pocket 27 is closed by a plug 75 30 which is threadedly secured in place and which is provided with ears or finger pieces 31.

A switch S², arranged upon the battery holder controls the supply of current to the 80 heating element.

The invention is susceptible of various changes in its form, proportions and minor details of construction and the right is herein reserved to make such changes as properly fall within the scope of the appended claim. 85

Having described the invention, what is claimed is:—

An electric heater comprising a shield shaped substantially in conformity with the 90 shape of a shoe and comprising a front section and a back section, means connecting one edge of the front section with one edge of the back section to permit of relative movement of said sections, means detachably connecting opposite edges of the front and back sections, an electric heating element carried within the front section, a source of current carried by the back section and means electrically connecting the heating element and 95 source of current. 100

In testimony whereof I affix my signature.

ISIAH WILLIAMS
